OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

THREAD CUTTER FOR LOOMS

Application filed December 9, 1930. Serial No. 501,080.

This invention relates to a thread cutter for use in automatic looms, designed for cutting weft ends closely adjacent the cloth selvage.

5 More particularly, the cutter is designed for cutting the weft ends extending from the selvage to an end holder of a magazine or to a thread cutting and gripping device on a shuttle placer.

10 It is the object of my invention to provide an improved thread cutter for such purposes, so designed that the thread will be cut when the lay is at back center, thus avoiding the possibility of dropping the weft end on the 15 shuttle race of the lay, where it may be carried into the warp shed.

20 My invention further relates to arrangements and combinations of parts which will be hereinafter described and more particularly pointed out in the appended claims.

A preferred form of the invention is shown in the drawings, in which

25 Figure 1 is a plan view of portions of a loom embodying my improved thread cutter; Fig. 2 is a sectional side elevation of the parts shown in Fig. 1;

30 Figs. 4 and 5 are sectional rear elevations, taken along the lines 4—4 and 5—5 in Fig. 2.

35 Referring to the drawings, I have shown a portion of a breast-beam 10, a lay 11 and a cutter-supporting bar 12 yieldingly mounted in brackets 13 on the breast beam 10. My improved thread cutter is mounted on a stand 20 slidable on the bar 12 and adapted to be clamped in a desired position by tightening a nut 22, threaded on the outer end of a recessed clamping plunger 24 (Fig. 3). By 40 tightening the nut 22, the stand 20 can be secured in any selected axial or angular position on the bar 12.

45 An angle bracket or cloth support 26 is secured to one side of the stand 20 and extends under the adjacent selvage of the cloth, as indicated in Fig. 1.

50 A pair of cutter bars 30 and 31 are loosely mounted on a stud 32 extending through the cutter bars 30 and 31 and through a corre-

sponding opening in the stand 20. The cutter bar 30 has an opening 34 (Fig. 5) which fits loosely over the head of a stud or rivet 35 secured in the inner face of the bracket 26. The cutter bar 30 is thus held from angular movement and acts as a fixed cutting blade.

55 A two-armed lever 40 is loosely pivoted on the stud 32 and its provided with a stud or rivet 42 extending into an opening 43 in the cutter blade 31. The blade 31 is thus mounted 60 for angular movement with the lever 40.

A spring 44 (Figs. 2 and 5) is seated in pockets in a lower surface of the stand 20 and in an upper surface of the lever 40 and acts to press the lever 40 and its associated cutter bar 31 downward to the open position shown in Fig. 2. A second spring 46 (Fig. 4) is mounted in a pocket 47 in the side of the lever 40 and forces the movable cutter bar 31 yieldingly against the cutting face of the fixed 70 cutter bar 30.

75 A strap 50 is secured at 51 to a depending end of the lever 40 and is secured at 52 to the front side of the lay 11.

Having described the details of construction of my improved thread cutter, the operation thereof is as follows:

80 The cloth C is drawn forward by the take-up mechanism over the bracket 26, and the weft ends W from the end holder or the shuttle placer will be drawn between the open jaws of the thread cutter, as indicated in Fig. 2.

85 As the lay 11 moves rearward and approaches back center, the strap 50 is tightened and thereupon swings the movable cutter bar 31 upward relative to the fixed cutter bar 30, thus severing the weft ends at the fell of the cloth when the lay is substantially at 90 back center.

95 In this position of the loom, the severed weft ends cannot fall on the shuttle race of the lay and consequently cannot be carried into the open shed by the shuttle. Consequently the defects heretofore caused by weaving weft ends into the cloth or fabric are effectively avoided.

100 My improved cutting mechanism is simple in construction, positive in operation, and

the cutter bars 30 and 31 can be easily removed for sharpening or replacement.

Having thus described my invention and the advantages thereof, I do not wish to be limited to the details herein disclosed, otherwise than as set forth in the claims, but what I claim is:

1. In a loom, a thread cutter, a stand, a stud mounted in said stand, a lever, a fixed cutting bar, and a movable cutter bar, said three parts being mounted on said stud, and said bars having openings remote from the axis of said stud, and transversely extending pins mounted in said stand and lever respectively and extending loosely into the openings in adjacent cutter bars, whereby one bar is fixed to said stand and the other bar is secured to said lever and both bars are readily removable and replaceable after the supporting stud is removed.

2. In a loom, a thread cutter mounted in a fixed position adjacent the cloth selvage and having fixed and movable cutter bars extending rearward, a lever connected to said movable cutter bar, and a flexible member directly connecting said lever to the lay, through which member said lever and movable cutter bar are continuously connected at all times to said lay and are operated to cut the weft ends by the direct action of the lay as the lay moves rearward and approaches back center, said member forming a lost motion connection as the lay approaches front center.

35. In testimony whereof I have hereunto affixed my signature.

OSCAR V. PAYNE.
